FREQUENCY RESPONSIVE RELAY

Filed April 28, 1937

FIG. 1.

FIG. 2.

UNITED STATES PATENT OFFICE

2,194,559

FREQUENCY RESPONSIVE RELAY

Winfield R. Koch, Merchantville, N. J., assignor
to Radio Corporation of America, a corpora-
tion of Delaware

Application April 28, 1937, Serial No. 139,347

6 Claims. (Cl. 250—27)

This invention relates to frequency responsive relays such as are useful for controlling the operation of an electric switch or for producing similar results, and has for its principal object 5 the provision of an improved relay system and method of operation whereby a desired effect may be readily produced in response to control impulses of a predetermined frequency or band of frequencies.

10 A further object of the invention is the provision of a radio receiver adapted to have its operation controlled in response to a high frequency sound such as a clap of the hands, a snap of the fingers, a hiss or the like.

15 As applied to radio receivers, the invention is advantageous in that it permits temporary silencing of the receiver for short periods of time such as are required for a telephone call, a short conversation or the like. As hereinafter 20 explained, the invention may be utilized to restore operation of the receiver either automatically after a predetermined time interval or manually in response to sound of a predetermined pitch or frequency. Thus operation of 25 the receiver is readily interrupted and reestablished by one seated in a chair located at a distance from the receiver, such control being available to any one of a number of persons located at different points in the same room, and without apparatus at the control points. The same 30 method of control may obviously be applied to the raising and lowering of a window, the opening and closing of a door and other similar operations.

35 The invention will be better understood from the following description when considered in connection with the accompanying drawing and its scope is indicated by the appended claims.

Referring to the drawing,

40 Figure 1 is a wiring diagram of a relay system which is operable to open and close a switch in response to successive sounds or wave trains of predetermined frequency, and

45 Figure 2 is a wiring diagram of a control circuit adapted to interrupt operation of a loud speaker for a predetermined time interval in response to sound of a predetermined pitch.

The system of Fig. 1 includes a microphone 10 which is interconnected with the operating 50 coil 11 of a switch 12 biased to its open position by means of a spring 13. Interposed between the microphone 10 and switch operating coil 11 are a step-up transformer 14, a band pass filter 15, concatenated amplifiers 16, 17 and 18, a double diode detector 19 and a trigger circuit 20 which

includes a pair of cross connected electron discharge devices 21 and 22. It will be noted that the double diode device 19 includes a cathode 23 and anode 24 which function to detect the high frequency control impulses and a cathode 25 and 5 anode 26 which function together with a filter network 27 as a socket power unit for energizing the plate or anode circuits of the various electron discharge devices of the circuit. Thus power is supplied to these various circuits from 10 the alternating current terminals 28 through the rectifier 25—26 and the filter 27 and heating current is supplied to the various cathodes from the terminals 28 through a resistor 29. The level or volume of the high frequency control im- 15 pulses delivered from the amplifier 18 through a coupling transformer 30 to the diode 23—24 may be adjusted by means of a resistor 31 con- 20 nected so as to permit control of the steady voltages applied to the amplifier 17.

Connected between the high potential lead 32 and the low potential lead 33 of the filter 27 are an adjustable resistor 34 which is provided for adjusting the potential of the diode cathode 23 and an adjustable resistor 35 which is pro- 25 vided for balancing the operation of the trigger circuit devices 21 and 22.

The devices 21 and 22 are provided with grids 36 and 37 which are subjected to a negative potential dependent on the voltage drop pro- 30 duced in a resistor 38 by the current of the diode 23—24, the action of which is delayed by the bias potential derived from the resistor 34. With these connections, a negative potential is 35 applied to the grids 36 and 37 when the peaks of the rectified control impulses are greater than the bias voltage applied to the diode 23—24.

The devices 21 and 22 are also provided with cross connected grids 38 and 39 which are sub- 40 jected to potentials dependent on the potential drops produced in the resistors 40 and 41 by the output currents of the devices 21 and 22. It will be observed that the grid 38 is connected to the low potential side of the resistor 41 through a resistor 42 which is shunted by a capacitor 43, 45 that the grid 39 is likewise connected to the resistor 40 through a resistor 44 which is shunted by a capacitor 45 and that the switch operating coil 11 is connected in the output circuit of the device 21 and is shunted by a capacitor 46.

With these connections, the trigger circuit 20 50 operates stably with either of the devices 21 and 22 open and the other closed. Thus, when the device 21 takes load current, the potential of the grid 39 is reduced to a point where the de- 55

vice 22 is closed and takes no load current and the potential of the grid 38 is consequently raised thus permitting the device 21 to take more current.

5 The operation of the system will be readily understood if it be assumed that the device 22 is taking load current and a control impulse is picked up by the microphone 10. Under these conditions, the grids 36 and 37 are temporarily 10 biased to cut-off by the potential produced in the resistor 38 by the rectified control impulses, the load current of the device 22 is interrupted and cessation of the control impulses permits the potentials of the grids 36 and 37 to return 15 to zero. Since the capacitor 45 in series with the grid 39 has not lost all its charge, the potential of the grid 39 is somewhat more negative than that of the grid 38, and the device 21 will take current, the potential of the grid 39 will 20 be reduced to a point where the device 22 takes no load current, and the switch 12 will be operated. A subsequent series of control impulses will permit the device 22 to take load current, interrupt the load current of the device 21 and 25 deenergize the switch operating coil 11 in a manner which is apparent from the foregoing explanation.

As previously indicated, the switch may be utilized to short circuit or open circuit a loud-speaker or to control a variety of other operations.

30 The system of Fig. 2 includes a switch 50 which is biased to its closed position by a spring 51 and is provided with an operating coil 52 arranged to be controlled in response to control impulses 35 picked up by a microphone 53 and supplied to it through a channel including a transformer 54, an amplifier 55, a tuned transformer 56 and a diode-triode device 57. Power for operating the control channel may be derived from any suitable 40 source such as a socket power unit 47, cathode heating current being supplied from the terminals 47' or otherwise as desired.

45 Interconnected with the diode 48-49 are a resistor 58 for applying a negative potential to the control grid 57' of the triode 49-57'-58 and a resistor 60 for automatically controlling the gain of the amplifier 55. In order to ensure quick opening and delayed closing of the switch 50, capacitors 61 and 62 are provided. The horn 63 50 of the microphone 53 may be so constructed with inlets 64 and 65 that it tends to transmit only sound waves of the control impulse frequency. While the switch 50 is arranged to short-circuit the loud speaker 66 of a loud speaker 67 for a predetermined time interval, it will be apparent 55 that it may be arranged to open circuit this loud speaker or otherwise control various types of devices. For the purpose of reducing the high frequency impulses delivered at the loud speaker 66 an absorption circuit 68 may be connected in 60 shunt to it if desired.

65 Operation of the system of Fig. 2 is controlled by high frequency impulses which are picked up by the microphone 53 through the acoustically filtered horn 63, amplified by the amplifier 55, detected and amplified by the diode-triode 57 and supplied to the switch operating coil. The length of the time interval during which the switch is maintained open after a train of control impulses is dependent on the sizes of the resistors 59 and 70 60 and the capacitors 61 and 62 which determine the rate at which the grid potentials return to a non-operating value.

75 It will be apparent that other trigger circuits than those illustrated may be utilized, thus gas-

eous electron discharge devices may be used in lieu of high vacuum devices, a push pull relay may be provided, or a suitably controlled mechanical relay of the notching or counting type may be arranged to actuate the switch. By utilizing 5 acoustic control frequencies higher than those usually present in radio broadcast reception or in the output of the radio receiver, accidental operation of the control circuit is readily avoided.

I claim as my invention:

1. The combination of a sound producing device, means for operating said device to produce sounds in a predetermined frequency range, means for controlling the operation of said device, means operable to energize said control 15 means in response to acoustic impulses of a frequency above said predetermined range, and means including a pair of electron discharge devices operable to energize said control means in response to acoustic impulses of a frequency 20 above said predetermined range and to deenergize said control means in response to a subsequent train of said impulses.

2. The combination of a device to be operated, means for controlling the operation of said device, means operable to energize said control means in response to acoustic impulses in a frequency range adjacent to the upper limit of audibility, means including a trigger circuit operable to energize said control means in response to 25 acoustic impulses in a frequency range adjacent to the upper limit of audibility, and to deenergize said control means in response to a subsequent train of said impulses, and means operable to delay the operation of said trigger circuit.

3. Frequency responsive relay means for controlling radio receiving apparatus and the like comprising, in combination, a microphone device responsive to audio frequency signals in the upper range of audibility, an amplifier for said microphone device provided with sensitivity control means whereby the sound level of the response of said device is determined, means for limiting the response of said amplifier to acoustical impulses at frequencies higher than those 45 normally present in radio broadcast reception or in the output of a radio receiving system whereby accidental operation of the frequency responsive relay means is prevented, a signal rectifier device coupled to said amplifier to provide a controlling potential responsive to acoustical impulses transmitted to said amplifier, means providing a controllable delay in the operation of said rectifier, a relay device having contacts for controlling the operation of a radio receiving 50 system and having an operating winding, and an amplifier having a control circuit connected with said rectifier device and an output circuit connected with said operating winding, whereby said operation is controllable in response to acoustical impulses above the normal range of audio frequency signal output from said receiving system.

4. Frequency responsive relay means for controlling radio receiving apparatus and the like 55 comprising, in combination, a microphone device responsive to audio frequency signals in the upper range of audibility, an amplifier for said microphone device provided with sensitivity control means whereby the sound level of the response of said device is determined, means for limiting the response of said amplifier to acoustical impulses at frequencies higher than those 70 normally present in radio broadcast reception or in the output of a radio receiving system whereby 75

accidental operation of the frequency responsive relay means is prevented, a signal rectifier device connected to said amplifier, a trigger amplifier controlled by the output from said rectifier comprising a pair of amplifier tubes, and a relay device having control contacts and an operating winding in circuit with one of said trigger amplifiers.

5. The combination with sound producing means having a predetermined frequency range of operation, of a frequency responsive relay means for modifying the acoustical output of said sound producing means, while being immune to operation in response to said acoustical output, 10 said relay means comprising an audio frequency amplifier, means for applying to said amplifier audio frequency signals in a frequency range above the normal frequency range of said sound producing means and in a relatively high audio 15 frequency range adjacent to the normal upper limit of audibility, a rectifier coupled to said amplifier to receive the high audio frequency

output therefrom and to convert the same into a controlling potential, means responsive to said potential for modifying the operation of said sound producing means, and means for modifying the application of said control potential to said last 5 named means whereby a predetermined operating characteristic is obtained for said last named means.

6. Frequency responsive relay means for silencing a radio receiver having a sound producing device comprising silencing means for said sound producing device responsive to a controlling current, an amplifier for supplying said current to said silencing means, and means for applying a controlling potential to said amplifier 15 in response to acoustical impulses in an audio frequency range above the frequency range of signals applied to said sound producing device through said receiver and of a predetermined amplitude. 20
